ATTORNEY

UNITED STATES PATENT OFFICE.

CHARLES F. WILLIAMS, OF NEW YORK, N. Y.

FOLDING CARRIER.

No. 901,858.

Specification of Letters Patent.

Patented Oct. 20, 1908.

Application filed March 6, 1908. Serial No. 419,427.

To all whom it may concern:

Be it known that I, CHARLES F. WILLIAMS, a citizen of the United States, and resident of New York, in the county of Kings and State 5 of New York, have invented certain new and useful Improvements in Folding Carriers, of which the following is a specification.

My invention relates to folding boxes or carriers particularly for shipping eggs or 10 other similar products.

The main object is to provide a construction which can be manufactured cheaply, folded compactly, quickly and easily set up or opened, and which will carry the contained articles safely. These advantages will be obvious when the construction is understood as hereinafter set forth and as illustrated in the accompanying two sheets of drawings.

20 Figure 1 is a perspective view of a carrier embodying the improvements of my invention, the cover being thrown back. Fig. 2 is an end view of the carrier partially folded, the end pieces being omitted. Fig. 3 is an 25 end view of a box similar to that shown in Fig. 2 distended, and with an auxiliary bottom. Fig. 4 is a perspective view of a fragment of an auxiliary bottom. Fig. 5 is a 30 perspective view of a carrier nearly open but without the end pieces and cover. Fig. 6 is a perspective view of a cover for the carrier of Fig. 5. Fig. 7 is a plan view of a blank for forming the body as shown in Fig. 1. Fig. 8 is a plan view of a blank for forming 35 the body as shown in Fig. 5. Fig. 9 is a plan view of the nest portion. Fig. 10 is an end view of the nest portion. Fig. 11 is a side view and partial section of the carrier of Fig. 5 with the cover of Fig. 6.

40 The blank for forming the preferred form of body is illustrated in Fig. 7, and comprises: a bottom composed of two parts, 1 and 2, a front 3, a back 4, a top 5, a flap 6, with a tongue to lock in the slits 7, and ends 45 8 and 9 with slightly tapered tuck flaps 10, 11, 12 and 13. The flap 6 may be tucked down back of the front as shown in Fig. 3.

The collapsible nest consists of a front strip 14, a back strip 15, a center strip or 50 partition 16, and a series of folding cross pieces such as 17, 18, 19, 20, 21 and 22, each of which has parts such as 23 and 24 pasted or glued to the strips 14 and 16 or 15 and 16, between which they are located. These cross 55 pieces with the front, back and partition walls form small pockets for receiving the

eggs or other articles. This form of nest has the great advantage of cheapness, in that it may be made by automatic machinery.

Although the nest is made separate from 60 the body of the carrier, the two are permanently united by pasting or gluing the front piece 3 and back piece 4, of the body to the front and back, respectively, of the nest. The body shown in Fig. 8 has only narrow 65 front and back strips, 3' and 4' so as to save the material. The form of carrier shown in Fig. 5 with this type of body is particularly adapted for use in shipping. Each type of body has a center crease, 25, and parallel 70 creases, 26 and 27, permitting the bottom to fold as shown in Fig. 2. Each cross piece has a center crease, 28, and parallel creases, 29 and 30, permitting it to fold as shown in Fig. 5. 75

When the box is opened the ends are folded up and the flaps 10, 11, 12 and 13 tucked into the end pockets so as to hold the parts in place with the pockets distended. In some cases the end pieces may be omitted as 80 the pockets will all remain distended if two of them are filled. A flat strip 31 (Fig. 4) inserted from either end beneath the nest and just above the folding bottom (Fig. 3) serves to hold the nest distended even when 85 empty. This auxiliary bottom greatly stiffens the box.

The cover shown in Fig. 6 is particularly serviceable with the carrier of Fig. 5. The top 32 has ends 33 and 34 and flaps 35 and 90 36 to tuck beneath the nest (Fig. 11). This furnishes a great reinforcement and in fact may be used as a handle to carry the box by, the ends or tuck flaps preventing collapse. As the carrier can be folded compactly it 95 can be distributed at small expense. The parts being all permanently united, it is very easy to set up the carrier, thus saving considerable time in packing.

What I claim is:—

1. An egg carrier comprising front and back walls, a central partition parallel to the front and back walls, a series of folding cross pieces permanently connected to the opposite sides of the partition and to the adjacent faces of the walls and having central vertical creases, and forming a single row of pockets on each side of the central partition, and a separately formed folding bottom connected to the front and back 105 walls and having a central longitudinal crease beneath said partition. 110

2. A folding carrier comprising front, back and central walls formed of separate strips, a series of creased folding cross pieces glued to the central wall and to the front 5 and back walls, some folding inwardly and others folding outwardly and forming a single row of pockets on each side of the central wall, and a body secured to the front and back walls and having a centrally creased 10 folding bottom.
3. A folding carrier comprising front and back walls, a central partition, folding cross pieces connected to the partition and to the walls and forming a single row of pockets 15 on each side of the central partition, a folding bottom centrally creased and secured to the front and back walls, and a cover hinged on an axis parallel to the bottom crease.
4. A folding carrier comprising a plurality 20 of parallel walls connected permanently by centrally creased cross pieces forming a plurality of rows of small collapsible pockets, a folding bottom permanently connected to the front and back walls, and end pieces 25 hinged to the bottom and having tuck flaps for holding the pockets distended.
5. A folding carrier comprising the combination of a nest portion consisting of front and back strips and folding cross strips secured thereto, and a separately formed body 30 consisting of front and back portions secured to the front and back strips of the nest portion and a bottom portion centrally creased so as to fold, together with means 35 for holding the body and nest distended.
6. A folding carrier comprising a collapsible nest having a plurality of rows of small
- pockets, and a separately formed body permanently secured to the nest and consisting of a folding bottom, front and back portions and end portions having tuck flaps for holding the nest distended. 40
7. A folding carrier comprising a collapsible nest having a plurality of rows of pockets, and a separately formed body secured 45 to the nest and consisting of a folding bottom, end pieces extending therefrom, front and back pieces extending from the edges of the bottom, and a cover extending from one edge of the back piece.
8. A folding carrier comprising a collapsible nest composed of a plurality of strips connected by folding cross pieces forming a plurality of rows of pockets, a folding bottom connected to the front and back and an auxiliary non-folding bottom adapted to 55 slide beneath the nest from one end.
9. A folding carrier comprising a collapsible nest composed of a plurality of strips connected by folding cross pieces forming a plurality of rows of pockets, a folding bottom secured to the front and back, a cover and end pieces with tuck flaps. 60
10. A folding carrier comprising the combination of a laterally collapsible nest portion open at the top and bottom, a separately formed bottom longitudinally creased so as to fold, and secured to the front and back of the nest portion and means for holding the nest distended. 65
